UNITED STATES PATENT OFFICE.

MAT BACEKOVICH, OF SABRATON, WEST VIRGINIA, ASSIGNOR OF ONE-HALF TO MATT SIKUTRICK, OF MONA, WEST VIRGINIA.

RAIL JOINT.

Application filed January 3, 1924. Serial No. 684,217.

To all whom it may concern:

Be it known that I, MAT BACEKOVICH, a citizen of Yugoslavia, residing at Sabraton, in the county of Monongalia and State 5 of West Virginia, have invented certain new and useful Improvements in Rail Joints, of which the following is a specification.

This invention relates to certain new and useful improvements in rail joints and has 10 for its primary object to provide an automatic locking device for retaining the meeting rail ends in position within a joint chair.

Another object of the invention is to provide 15 a rail joint wherein a spring plate or strip removably supported upon the bottom wall of the joint chair is adapted for interlocking engagement with the lower faces of the meeting rail ends to retain the rail 20 ends in an anchored position within the joint chair.

With the above general objects in view and others that will become apparent as the 25 nature of the invention is better understood, the same consists of the novel form, combination and arrangement of parts herein-after more fully described, shown in the accompanying drawing and claimed.

In the drawing, wherein like reference 30 characters designate corresponding parts throughout the several views,

Figure 1 is a side elevational view, partly 35 in section showing the meeting ends of rails anchored within a joint chair with the resilient locking strip interlocked with the adjacent ends of the meeting rails.

Figure 2 is a horizontal sectional view taken on line II—II of Fig. 1,

Figure 3 is a horizontal sectional view 40 taken on line III—III of Fig. 4 showing the resilient locking strip supported upon the bottom wall of the joint chair,

Figure 4 is a cross-sectional view taken on line IV—IV of Fig. 1,

Figure 5 is a cross-sectional view taken 45 on line V—V of Fig. 1,

Figure 6 is a perspective view of one 50 end of a rail in inverted position showing the pocket in the lower face of the rail base for cooperation with the resilient locking strip, and

Figure 7 is a perspective view of the locking strip.

Referring more in detail to the accompanying drawing, the reference numeral 1

designates the meeting rail ends that are anchored in the joint chair, the rail ends being of identical construction and each embodying the usual tread 2, web 3 and the base 4. As shown more clearly in Figs. 1 60 and 6, a recess or pocket 5 is formed in the lower face of the rail base 4 and is of gradually increasing depth from the point 6 spaced from the end of the rail to the abutment wall 7 adjacent the rail end. 65

The joint chair includes a base plate 8 having spike receiving openings 9 adjacent the corners thereof for anchoring the joint chair to supporting ties while a longitudinally extending centrally positioned recess 70 10 is formed in the upper face of the base plate 8 that gradually increases in depth as at 10^a toward the center of the plate.

A resilient rail engaging locking strip 11 is disposed in the recess 10 and removal 75 thereof is facilitated by the end notches 12 in the end walls of the recess as shown in Fig. 3. The resilient strip 11 intermediate the ends thereof is provided with a pair of lugs 13 formed integral with the 80 strip and of gradually increasing height from the points 14 to the shoulders 15 that are spaced from each other to provide an intervening recess 16.

One side of the base plate 8 of the joint 85 chair has a fish plate 17 formed integral therewith while an upstanding flange 18 carried by the other side of the base plate 8 cooperates with removable splice bars 19, securing bolts 20 passing through the splice 90 bars 17, 19 and the rail webs 3 for further anchoring the meeting rail ends in position.

With the splice bar section 19 removed, the meeting rail ends may be laterally moved 95 into position or assembled in the rail chair by endwise movement with the rail base 4 supported upon the upper face of the base plate 8 of the joint chair and with the adjacent ends of the rail faces moving over the upper surface of the resilient strip 11 to engage the lugs 13 for depressing the same during the assembling of the rail sections. When the meeting rail ends are in the position shown in Fig. 1, the shoulder 15 of the lug 13 escapes the shoulder 7 in the recess 5 of the rail base with the lug 13 bodily moving into the rail base recesses to form an interlocking connection between the meeting rail ends and the joint chair, the central portion of the resilient strip at this time be 100 105 110

ing elevated from the groove portion 10^a in the base of the joint chair and so retained by the resiliency thereof.

While there is herein shown and described the preferred embodiment of the present invention, it is nevertheless to be understood that minor changes may be made therein without departing from the spirit and scope of the invention as claimed.

10. What is claimed as new is:—

1. In a rail joint of the class described, meeting rail ends, a joint chair supporting the rail ends, and cooperating means carried by the chair and rail ends for automatically locking the rail ends in the chair, said cooperating means including a resilient strip carried by the joint chair adapted for interlocking engagement with the rail ends.

2. In a rail joint of the class described, meeting rail ends, a joint chair supporting the rail ends, cooperating means carried by the chair and rail ends for automatically locking the rail ends in the chair, said cooperating means including a resilient strip carried by the joint chair, spaced upstanding beveled lugs carried by the strip, the lower faces of the rail ends having recesses therein for the reception of the strip lugs.

3. In a rail joint of the class described, meeting rail ends, a joint chair supporting the rail ends, cooperating means carried by the chair and rail ends for automatically locking the rail ends in the chair, said cooperating means including a resilient strip carried by the joint chair adapted for interlocking engagement with the rail ends, an integral splice bar carried by one side of the base, a removable splice bar for the other side and lock bolts passing through the splice bars and rail webs.

4. In a rail joint of the class described, meeting rail ends, a joint chair supporting the rail ends, cooperating means carried by the chair and rail ends for automatically locking the rail ends in the chair, said cooperating means including a resilient strip carried by the joint chair, spaced upstanding beveled lugs carried by the strip, the lower faces of the rail ends having recesses therein for the reception of the strip lugs, an integral splice bar carried by one side of the base, a removable splice bar for the other side and lock bolts passing through the splice bars and rail webs.

In testimony whereof I affix my signature
MAT BACEKOVICH.
